UNITED STATES PATENT OFFICE.

LYMAN C. STEWART AND MARSHALL A. QUINN, OF ROANOKE, VIRGINIA.

MOLD FOR BUILDING POURED CONCRETE STRUCTURES.

1,163,480.

Specification of Letters Patent.

Patented Dec. 7, 1915.

Application filed May 21, 1914. Serial No. 840,098.

To all whom it may concern:

Be it known that we, LYMAN C. STEWART and MARSHALL A. QUINN, citizens of the United States, residing at Roanoke, in the 5 county of Roanoke and State of Virginia, have invented certain new and useful Improvements in Molds for Building Poured Concrete Structures, of which the following is a specification.

10 Our invention relates to an improvement in molds for building poured concrete structures, and the present invention is a collapsible core.

15 Heretofore in inventions of this general type, difficulty has been encountered in withdrawing the core after the concrete has set. This difficulty has been largely due to the fact that the core was not collapsible, both widthwise and lengthwise.

20 Our present invention provides for both, and first of all the collapse widthwise, or as to thickness, which quickly removes the sides of the core from the molded walls and permits collapse lengthwise to follow, it being particularly advantageous where a core 25 is employed, as in all cases in which the area of the lower edge either as to width and length, and sometimes both, may be greater than that of the upper edge; and with this 30 in view, our invention consists in telescoping sides with spacing means therebetween on the toggle-joint principle, which when adjusted in one position holds the sides rigidly apart, and when in another position 35 moves them toward each other in a collapse of the core, along with means for varying the width at top and bottom, and other novel features of construction and combinations of parts, which will be hereinafter 40 described and pointed out in the claims.

In the accompanying drawings: Figure 1 is a view illustrating a portion of a wall, with some of the outer part broken away to show the internal construction and two or 45 more cores in position therein, Fig. 2 is a transverse section through the core, showing it in position in the wall, Fig. 3 is a horizontal section through the core, Fig. 4 is a view in side elevation with parts broken 50 out, Figs. 5 and 6 are enlarged details, and Fig. 7 is a slightly modified view of the sliding connection at the edges of the core.

The core is made up of four main parts 55 bent from sheet-metal, and constituting two sides, and each side is composed of two

members 1 and 2 slidably connected together at their upper and lower edges in any approved form, as for instance by means of the inturned flanges 3, 3, on the sections 1, 1, and overlapping and embracing flanges 4, 4, on section 2, which receive and are slidably connected with the flanges 3, 3. These constitute the sliding, telescoping joints, whereby the lengthening and shortening of the core is made both possible and convenient. 65 As a slight modification of this form of joint, the construction illustrated in Fig. 7 might be adopted, in which the edges are concentrically crimped together as at 3' and 4'.

The ends of the core are formed by the 70 overlapping, inturned edges 5, 5, and 6, 6, and these ends preferably incline at an angle from one edge of the mold to the other, although not necessarily, and when they do thus incline, it obviously makes one edge of the core always longer than the other. As stated, this is preferred, for the reason that it gives the required shape to the bond 7 which is to be formed between the two sides 75 of the wall being molded.

The mechanism for holding the sides apart and for collapsing the core widthwise, is located and housed within the sheet-metal core, and it consists in a plurality of toggle-joints 8, 8. These may be variously constructed, and one member of each toggle is connected with its corresponding member at the other edge of the core, preferably through the medium of an integral rod 10, so that the toggle at both edges are simultaneously operated by adjusting either one, and the center toggle 11 may be operated through a connecting-rod 12 pivotally connected at one end with the toggle and at the other end with the arm 13 projecting from 90 one of the rods 10.

It is desirable to adjustably connect the toggle-members together, for the reason that in many, and perhaps most instances in building a wall, it is desirable to make the lower edge of the core wider than the upper edge. As a simple means of providing for this, and accomplishing it quickly, one member of each toggle may have a slot, such as 14, adapted to receive a bolt or pin 15 on the other member, which latter is caused to take a position in either of the extreme ends 16 or 17 of the slots, whereby to widen or narrow the edge as the case may be.

The rods 10 form braces to prevent the 110

crushing of the sides, which are preferably of sheet metal, by the concrete when it is poured in the formation of the wall. Without this reinforcement there is the liability 5 of the sides being forced inward, and thereby by making it difficult to remove the core from the wall.

In the construction of the wall, the core is alternately inverted, so that the concrete 10 bond 7 would first be V-shaped and then diamond-shaped, and these diamond-shaped bonds are staggered. That, however, is entirely within the discretion of the builder, but the essential feature is the provision 15 whereby the core may first be collapsed as to width, so that the overlapping, telescoping part and the widened lower edge (where this plan is followed) can be brought together to clear the formation, following 20 which the length of the core is reduced to clear the bonds. To facilitate placing and holding the core against lateral displacement, lugs 18, 18, are provided, one at each of the eight corners of the core.

25 More or less slight changes might be made in the form and arrangement of the several parts described without departing from the spirit and scope of our invention, and hence we do not wish to be limited to the exact 30 construction herein set forth, but:—

We claim:—

1. A collapsible core comprising flexible sides, rods pivotally mounted along the inside thereof, links on the ends of the rods, 35 the links of each rod having engagement

with the links of the adjacent rod for connecting the sides together, said links adapted to be actuated for expanding the core, and maintaining the sides in said position and for causing a collapse of the core by 40 drawing the sides toward each other.

2. A collapsible core for molding, comprising flexible telescopic sides and ends, rods pivotally mounted along the inside thereof, links on the ends of the rods, the 45 links of each rod having engagement with the links of the adjacent rod for connecting the sides together, said links adapted to be actuated for expanding the core and maintaining the sides in said position and for 50 causing a collapse of the sides widthwise, thereby permitting the collapsing of the core lengthwise.

3. A collapsible core for molding comprising extensible sides and ends, rods pivoted vertically on the inner faces of the sides, toggle joints connecting the rods across from opposite sides, means for lengthening and shortening said toggle joints, and a connecting rod extending from one vertical rod to another whereby to operate the toggle joints at different points, within the 55 collapsible core, simultaneously.

In testimony whereof we affix our signatures, in the presence of two witnesses.

LYMAN C. STEWART.
MARSHALL A. QUINN.
